UNITED STATES PATENT OFFICE.

HENRY PERSSON, OF MILFORD, MASSACHUSETTS.

FLOOR JACK.

Application filed September 5, 1924. Serial No. 736,076.

To all whom it may concern:

Be it known that I, HENRY PERSSON, a citizen of the United States, residing at Milford, in the county of Worcester and 5 State of Massachusetts, have invented certain new and useful Improvements in a Floor Jack, of which the following is a specification.

This invention relates to improvements 10 in flooring clamps or jacks and has for its principal object to provide a simple and efficient device for use in connection with the laying of floor or ceiling boards of the tongue and groove character.

15 One of the important objects of the present invention is to provide a floor jack of the above mentioned character, wherein the same is of such construction as to enable the device to be readily and easily placed 20 in position for use and will save considerable time and labor in laying floor or ceiling boards.

A further object of the invention is to provide a floor jack of the above mentioned 25 character, which is simple in construction, inexpensive, strong and durable and furthermore adapted for the purposes for which it is designated.

Other objects and advantages of this invention will become apparent during the 30 course of the following description.

In the accompanying drawing forming a part of this specification and in which like numerals designate like parts throughout 35 the same:

Figure 1 is a side elevation of the floor jack embodying my invention, and

Figure 2 is a top plan view thereof.

In the drawing wherein for the purpose 40 of illustration is shown the preferred embodiment of my invention, the numeral 1 designates an elongated supporting arm which is disposed horizontally and carries on the forward end thereof the transversely 45 extending head 2, the latter being provided in its outer longitudinal face with the grooves 3 for engagement with the tongue of each of the boards which are to be laid in the manner well known in the art. The 50 rear end of the arm 1 is provided with a longitudinally extending slot 4 and the purpose thereof will hereinafter be more fully described.

Fulcrumed at its lower end on the projection 5 formed on one side of the arm 1 adjacent the head 2 is the elongated operat-

ing lever 6. The fulcrum for the lever is illustrated at 7. The lever 6 extends upwardly from the horizontally disposed arm 1 and the upper end thereof is slightly offset as illustrated at 8 to facilitate the easy operation thereof.

Pivotedly supported at its forward end to the operating lever 6 directly above the fulcrum 7 is the foot member 9. The pivotal connection between the foot and the lever is shown at 10 in the drawing. The foot 9 is inclined downwardly and extends adjacent the side of the arm 1 on which the projection 5 is formed and terminates at its lower end in the sharpened spur 11 the latter being adapted for engagement with the floor joists when the floor jack is in use.

For the purpose of holding the lever and foot in their proper positions and to further permit the movement thereof in an efficient manner a headed stud 12 extends laterally from the lower portion of the foot 9 and is adapted for slidable movement in the slot 4 formed in the rear end of the arm 1. The stud and slot cooperate to provide a guide means for facilitating the sliding movement of the arm 1 and the head 2 thereon whereby the board, the tongue of which is engaged by the groove 3 of the head 2, may be moved into engagement with the adjacent board in the manner well known in the art.

The provision of the spur 11 on the rear end of the foot 9 will prevent any possibility of the floor jack from creeping or otherwise moving out of its proper position during the laying of the floor or ceiling boards. The simplicity in which my device is constructed enables the same to be easily and efficiently operated and will save considerable time and labor in carrying out the purposes for which the same is designated. Furthermore when the floor jack is not in use, the same may be readily folded into such position as to occupy a minimum amount of space.

While I have shown the preferred embodiment of my invention, it is to be understood that various changes in the size, shape and arrangement of parts may be resorted to without departing from the spirit of the invention and the scope of the appended claim.

Having thus described the invention what I claim is:

A floor jack comprising an arm provided at one end with an integral head provided

with a groove in one side for reception of a bored tongue, the opposite end of said arm being bifurcated to provide a guide slot between the furcations, a lever fulcrumed at its lower end upon said arm and adjacent said head, the upper free ends of the lever being offset, a foot pivotally connected at one end to said lever adjacent the point of pivotal connection of the latter, the pivot 10 of the foot being close to and normally

above the lever pivot, the intermediate portion of said foot extending across the said arm and the free end of the foot being provided with a pointed spur, and a bolt connected to said foot and extending slidably 15 between the furcations.

In testimony whereof I affix my signature.

HENRY PERSSON.
